PORTABLE WIER

Ernie G. Jones, Jr., 4021 Berrendo Drive, Sacramento,
Calif. 95825, and Edwin W. Schwenk, Sacramento,
Calif. (4905 St. Lynn Lane, Carmichael, Calif. 95608)

Filed June 6, 1968, Ser. No. 12,235

Term of patent 14 years

Int. Cl. D23—01

U.S. Cl. D23—1

FIG. 1

FIG. 2

FIG. 6

FIG. 3

FIG. 4

FIG. 5

FIG. 7

FIGURE 1 is a front perspective view of a portable wier showing our new design;

FIGURE 2 is a top plan view;

FIGURE 3 is a front end elevational view, the opposite end being substantially similar in appearance;

FIGURE 4 is a side elevational view, the opposite side being substantially similar in appearance;

FIGURE 5 is a bottom plan view;

FIGURE 6 is a fragmentary sectional view to an enlarged scale showing details of the three piece wier gate in installed position, the plane of the section being indicated by the line 6-6 in FIGURE 1; and,

FIGURE 7 is a fragmentary sectional view to a scale larger than the scale of FIGURE 6, showing details of

one of the wier gate retention clips, the plane of the section being indicated by the line 7-7 in FIGURE 1.

We claim:

The ornamental design for a portable wier, as shown and described.
